UNITED STATES PATENT OFFICE.

JOHN NILSEN SELVIG, OF CHICAGO, ILLINOIS, ASSIGNOR TO WESTERN ELECTRIC COMPANY, INCORPORATED, OF NEW YORK, N. Y., A CORPORATION OF NEW YORK.

WIRE-DRAWING MACHINE.

Application filed July 12, 1924. Serial No. 725,660.

This invention relates to improvements in horizontal sectional view taken on the line 7—7 of Fig. 5;

An object of the invention is to control the supply of lubricant to the die and drawing element of a wire drawing machine by the wire being drawn.

In accordance with one feature of the invention a wire drawing machine is provided with a capstan for drawing a wire through reducing dies which capstan may be connected to and disconnected from a driving mechanism by a clutch, the dies being mounted in a hollow die block arranged above the capstan. Lubricant is supplied to the interior of the die block for lubricating the dies, in such quantity that it drains onto the capstan for lubricating it, a valve being provided for controlling the lubricant supply, the clutch and valve being so connected that the capstan is disconnected from the driving mechanism and the valve closed to discontinue the supply of lubricant to the die in the event that the wire breaks during the drawing operation.

Other features and advantages of the invention will be set forth in the following description and particularly pointed out in the appended claims.

The accompanying drawings illustrate one embodiment of the invention, in which—

Fig. 1 is a front elevation, parts being broken away, showing a wire drawing machine embodying the features of the invention;

Fig. 2 is an enlarged fragmentary side elevation, partly in section, showing the mechanism for simultaneously starting the capstan and opening the valve through which lubricant is supplied to the die block and also for simultaneously stopping the capstan and closing the valve to discontinue the supply of lubricant to the die block in the event that the wire breaks;

Fig. 3 is an enlarged detail view showing the connection between the rod for operating the capstan clutch and the levers for opening and closing the lubricant supply valve;

Fig. 4 is a fragmentary sectional view taken on the line 4—4 of Fig. 2 showing a front elevation of some of the valve parts;

Figs. 5 and 6 are enlarged fragmentary views in vertical section, parts being shown in elevation, of a portion of the lever mechanism for operating the capstan clutch;

Fig. 7 is an enlarged fragmentary hori-

Fig. 8 is an enlarged fragmentary disassembled perspective view showing in detail a portion of the mechanism illustrated in Fig. 5, and

Fig. 9 is an enlarged fragmentary front view of a portion of the leverage mechanism shown in Fig. 1.

Referring now to the drawings in detail in which like reference numerals designate similar parts throughout the several views, 11 represents a framework which supports a compartment 12 of substantially rectangular shape having top, bottom, back and side walls 13, 14, 15, and 16 respectively. The front of the compartment may be closed by a suitable door or doors (not shown). The wire drawing apparatus is mounted within this compartment and comprises a horizontally disposed shaft 18 upon which is mounted a plurality of integral capstans 17—17 of different diameters. The shaft 18 is driven through suitable gearing by a motor (not shown) carried by the framework and is coupled to and disconnected from the capstans through a clutch mechanism hereinafter described. Mounted above the shaft 18 are a plurality of sheaves 19 independently rotatable upon a horizontally disposed shaft 20 suitably supported within the compartment 12. Mounted between the sheaves 19 and capstans 17—17 is a die block 21 carried by a bracket 22 secured to the back wall of the said compartment. For a detailed illustration and description of the sheaves 19 and the driving mechanism for the capstan shaft 18 reference is made to applicant's co-pending application, Serial No. 541,633, filed March 7, 1922. The details of this construction have been omitted from the present application for the sake of simplicity, since a full description of the sheaves and driving mechanism for the capstan shaft 18 is not essential to a complete understanding of the present invention.

The clutch mechanism for coupling the capstans 17—17 to and disconnecting them from the driving shaft 18 is shown in Fig. 2, the clutch being illustrated in its operated position. The shaft 18 is in the form of a sleeve which projects through a horizontally and centrally disposed opening made through the capstans 17—17. This sleeve carries adjacent its outer end an annular

105
95
100
110

member 70 fast thereto which has secured to it by means of a pin 71 a plurality of clutch disks 72. Alternately mounted between the clutch disks 72 are clutch disks 73 which are secured by a pin 74 to the inner peripheral wall of a cup-shaped opening 75 made in the capstans 17-17. The disks 72 and 73 are movable longitudinally on the pins 71 and 74 respectively, and when pressure is exerted 5 to force the disks together they form a driving connection between the capstans 17-17 and the sleeve 18, as is readily understood. The means for forcing the disks 72 and 73 together comprises a plate 76 which engages the outermost disk, and when the said plate is moved toward the right, into the position shown serves to force the disks together sufficiently to cause them to rotate as a unit. The plate 76 is fastened to one end of a shaft 10 77 mounted within the sleeve 18. A transverse pin 79 is secured in the shaft 77 and projects through diametrically opposite longitudinal slots 80 cut in the sleeve 18 and engages an annular channel formed in the interior wall of a housing 78 so as to be movable longitudinally therewith but free to rotate independently of the said housing. Through the medium of the pin 79 and slots 80, the shaft 77 and housing 78 are movable 15 together longitudinally of the sleeve 18. Means (not shown) is provided for preventing the housing from turning but permitting it to move longitudinally of the sleeve 18. Secured to the sides of the housing 78 at 20 diametrically opposite points are pins 81 which receive the bifurcated ends of a forked member 82 which is pivoted at 83 along with a link 84. The link 84 has secured to its free end a pin 85 which fits within a slot 25 formed in the upper end of a vertically reciprocable rod 86.

For a more detailed illustration and description of the clutch mechanism per se reference is made to the copending application 45 of W. F. Hosford, Serial No. 566,206, filed June 6, 1922.

When it is desired to revolve the capstans 17-17 the rod 86 is moved downwardly, as viewed in Fig. 2, by means of a foot treadle, 50 handle, or other suitable means (not shown). As the rod 86 moves downward the housing 78 is moved to the right longitudinally of the shaft 18 through the medium of the link 84 and forked member 82 into the position shown in Fig. 2. The housing 78 carries with it, the shaft 77, through the medium of pin 79, causing the plate 76 carried by the shaft to exert sufficient pressure on the disks 72 and 73 to cause them to form 55 a driving connection between the sleeve 18 and capstans 17. When the means for lowering the rod 86 is released, the said rod is restored to its initial position and the housing 78 and shaft 77 moved toward the left, 60 as viewed in Fig. 2, by means of energy

stored in a compression spring 87, which has one of its ends in engagement with the shaft 77 and its other end against a plug 88 screwed within the end of the sleeve 18. The housing 78 in moving toward the left, as above described, engages a brake member 89 carried thereby against an annular member 90 secured to the capstan and serves to stop the rotation thereof.

Referring now to the lubricating system, 75 the die block 21 comprises a hollow, horizontally disposed body portion 23 having secured thereto shelves 24 and 25, each of which is adapted to support a series of dies thereon (not shown). One end of the body 80 portion 23 is provided with an opening 27 (Fig. 2) through which projects a valve casing 28 provided with a series of openings 29 which communicate with the interior of the body portion 23. Suitably supported within 85 in the valve casing 28 is a valve 30 which is normally held on its seat by a compression spring 31. In communication with the valve 30 and suitably supported is a pipe 32 connected by an elbow 33 with a vertically disposed pipe 34 (Fig. 1) which is connected to the outlet port of a pump 35. The intake port of the pump has connected thereto a pipe 36 which is suitably supported within 90 an opening 37 formed in the bottom wall 95 40 of the compartment 12. Disposed above the bottom wall 40 and parallel therewith is a screen 38, the purpose of which will be hereinafter described.

When the capstans 17 are set in motion 100 by lowering the rod 86, as previously described, the valve 30 is simultaneously opened by means of an arm 39 which is turned counter clockwise about its pivot 91 and through a second arm 41 movable therewith and engaging the end of the valve stem 105 the valve 30 is moved off of its seat. The arm 39 is given the movement just described by means of a plunger 92 reciprocably mounted within a bearing 93 carried by the 110 back wall 13 of the compartment 12, one end of the said rod being in engagement with the arm 39 and its other end having a pin and slot connection with a bell-crank lever 94 pivoted at 95 to a bracket 96 suitably supported by the framework of the machine. Pivoted to the bell-crank lever 94 is one end 115 of a link 97, the lower end of which is pivoted at 98 to an arm 99 pivotally mounted upon a stud 100 carried by the framework 120 of the machine. The arm 99 is provided with a projection 101 which fits within a recess 102 formed in the rod 86 (Fig. 3) so that the link 97 moves in a reverse direction as compared with the rod 86. 125

The pump 35 serves to draw lubricant placed in the compartment 12 and lift it into the interior of the body portion 23 of the die block, from which it is forced on top 130 of the dies supported on the shelves 24 and

25 through a series of openings 26 formed in each of the shelves 24 and 25. For a detailed description and disclosure of the construction of the die block reference is made 5 to the copending application of F. S. Kochendorfer, Serial No. 566,285, filed June 6, 1922. The lubricant is supplied to the dies in such quantities that it overflows the shelves 24 and 25 and drops onto the cap- 10 stans 17 mounted beneath the die block and serves to thoroughly lubricate said capstans. Excess lubricant supplied to the capstans drains therefrom through the screen 38 onto the bottom 40 of the compartment, 15 from which it is again lifted into the interior of the die block by the pump 35.

Due to the construction of the lubricating system just described and the operative connection between the clutch for stopping and 20 starting the capstan and the valve for controlling the supply of lubricant to the die block, the wire drawing apparatus is only lubricated during such times as it is in operation, and whenever the capstan is stopped 25 which may be caused by the operator disengaging the clutch or by the breakage of the wire during the drawing operation the lubricant is cut off. The mechanism for causing the clutch to be operated upon breakage 30 of the wire will be hereinafter described. Since the flow of lubricant is controlled automatically by the stopping and starting of the capstan, whenever the capstan is in operation sufficient lubricant is insured, the 35 supply of which is not dependent upon the discretion of the operator, and when the capstan is idle no lubricant is supplied to the dies or capstan, which might interfere with the adjustment of the apparatus or 40 stringing of the machine.

A supply of wire to be reduced in diameter is carried by a supply spool 50 suitably mounted at the front of the machine. The wire is guided from the supply spool over 45 and under pulleys 51 and 52 respectively (Fig. 1) and then over the rear sheave 19 and through the first reducing die (not shown) carried by the die shelf 24. The wire is then wound once around the capstan 50 of smallest diameter, after which it is passed upward and over the next sheave 19 and through the next reducing die carried by the die shelf 25. The wire is then wound around the next capstan and then again over 55 the next sheave 19 and through the next reducing die, etc.; until it is finally drawn down to the desired diameter by the last reducing die. From the final reducing die the drawn wire passes around the capstan 17 of largest diameter and is guided by a pulley 57 rotatably mounted on a stationary arm 58 adjustably positioned on the shaft 20 to a pulley 59 carried by a lever 60. From the pulley 59 the wire is led to a take-up spool 60 65 65 (dotted outline Fig. 1), driven by suitable

mechanism (not shown). For a detailed illustration and description of the mounting for the spool 61 reference is made to applicant's co-pending application, Serial No. 78,814, filed January 2, 1926.

As previously stated, the clutch mechanism shown in Fig. 2 is illustrated in its operated position in which the capstans 17-17 are connected with the sleeve 18. When it is desired to release the clutch 70 mechanism and stop the operation of the capstans 17-17, a knob 125 is moved to the left, as viewed in Fig. 6. This knob is mounted on the projecting end of a rod 126 by a pin 127 fastened to the knob which 75 fits within a longitudinal slot 128 cut in the rod. Due to this connection the knob 125 may move a limited distance on the rod without causing any movement of the latter. The rod 126 is reciprocably mounted 80 within a bracket 129 fastened to the front wall of the compartment 12. When the capstan is operating, the rod 126 is held in the position shown in Fig. 6 by means of a spring pressed pawl 130 which engages a 85 notch cut in the rod. When the knob 125 is moved to the left to stop the operation of the capstan, as above described, a shoulder 131 formed on the knob engages a projection 132 integral with the pawl 130 causing 90 the said pawl to be rotated counter-clockwise and free the rod 126 which is moved toward the left by a compression spring 153 (Fig. 5) to be hereinafter more fully described. Pivoted to the rod 126 at a point 133 is a lever 134 which is pivoted at one end to the bracket 129 and at its other end to one end of a link 135, the other end of the link 135 being pivoted to a bell-crank 95 lever 136 pivotally mounted upon a bracket 100 137 secured to a portion of the framework of the machine. The bell-crank lever 136 is also pivoted to one end of a link 138, the other end of which is connected to the laterally extending arm 139 of a bell-crank lever 105 140. This lever is pivoted on a stud shaft 141 (Fig. 5) carried by a bracket 142 fastened to a portion of the framework 11. The other arm 143 of the bell-crank lever 140 is bifurcated to straddle one end of a 110 rod 144 to which it is pivotally connected by means of a stud 145. The rod 144 is reciprocably mounted within the bracket 142 and is prevented from turning by means of a pin 146 carried by the said bracket which 115 fits within a longitudinal slot 147 cut in the said rod. The inner end of the rod 144 has a tongue portion 148 and a lug 149 on either side thereof as shown in Figs. 7 and 8. When the capstan is operating, the end of the rod 144 fits within a longitudinal slot 150, cut in a block 151, in a position in 120 which the lugs 149 rest beneath lugs 152 which narrow the front portion of the slot 125 to a width which is only sufficient to receive 130

the tongue portion 148. When the knob 125 is moved as previously described, through the rod 126, lever 134, link 135, bell-crank 136, link 138 and bell-crank 140, the rod 144 is moved toward the right, as viewed in Fig. 5, by the compression spring 153 which bears at one end against a shoulder formed on the rod 144 and at its other end against a plug 154. The rod 144 is moved a sufficient distance to carry the lugs 149 from beneath the lugs 152 and permit the block 151 to freely slide on the tongue 148. The block 151 is circular in cross section and is reciprocably mounted within an opening formed in a projecting portion 155 carried by the framework of the machine. When the block 151 is freed by the rod 144, it is moved downwardly, as viewed in Fig. 5, by means of energy stored in a compression spring 156 which bears at one end against a collar 157, which is in engagement with lock nuts 158 threaded on a rod 159, the other end of said spring engaging the bottom of a cup-shaped opening 160 formed in the block 151. In moving downwardly the block 151 engages the upper edge of a vertically disposed casing 161 into which an enlarged portion of the rod 159 projects and to which the said rod is attached by means of a pin 162 carried by the casing which is movable within a longitudinal slot 163 cut in the rod 159. The tension of the spring 156 is sufficient to couple the block 151 to the casing 161 and rod 159 so that these three parts move together as a unit during the downward movement of the block. The casing 161 at its lower end is suitably pivoted to a foot pedal (not shown). Threaded on the upper end of the rod 159 are nuts 165 and 166 which clamp between them a block 167 carrying at diametrically opposite points pivot pins 168 upon which the bifurcated ends of the lever 164 are pivoted. The lever 164 is pivotally mounted as indicated at 202 upon a bracket 203 (Fig. 2) carried by the framework 11, and is suitably connected by a link 204 with the rod 86 which as heretofore described controls by its movement the engagement and disengagement of the capstan clutch and simultaneously the opening and closing of the valve 30 controlling the supply of lubricant to the die block 21. After the block 151 has been coupled to the casing 161 and rod 159 through the medium of the spring 156, as previously described, these three elements are moved downwardly, a distance limited by the engagement of the brake member 89 with the annular member 90 carried by the capstan which movement will be described presently, the lever 164 being rocked clockwise about its pivot 202 by an upward movement of the rod 86. The rod 86 is moved in this direction, through the link 84, fork member 82 and casing 78, by the rod 77 which is moved toward the left, as viewed in Fig. 2, by means of energy stored in the compression spring 87 which is released by the actuation of the knob 125 as hereinbefore described. The spring 87 has one of its ends in engagement with the said shaft and its other end against the plug 88 screwed into the end of the shaft 18. The rod 77 moving toward the left carries with it the plate 76, thereby relieving the pressure on the clutch disks 72 and 73 so that these disks no longer couple the capstans 17-17 to the sleeve 18. The housing 78 is limited in its movement toward the left, as hereinbefore described, by the engagement of the brake member 89 carried thereby with the annular member 90 rotatable with the capstans 17-17, the braking surface serving to stop the rotation of the capstans after the clutch mechanism is released.

When it is desired to start the capstans the foot pedal (not shown) is depressed, which movement immediately lifts the casing 161 and block 151 resting at this time upon its upper surface, the latter in its upward movement compressing the spring 156. After moving the block 151 upward a distance limited by the pin 162 and slot 163 the upward movement of the casing 161 is transmitted to the rod 159, the continued upward movement of which rocks the lever 164 clockwise as viewed in Fig. 2 about its pivot. This movement of the link 164 draws the rod 86 downwardly (Figs. 2 and 3) which through the medium of the link 84, fork member 82, and housing 78 moves the rod 77 to the right, as viewed in Fig. 2, against the spring 87. For a detailed illustration and description of the operative connection between the foot treadle and rod 86, reference is made to applicant's copending application, Serial No. 566,385, filed June 6, 1922. The complete details of this connection have been omitted from the present application for the sake of simplicity and since they are not essential to a complete understanding of this invention. As the casing 78 and rod 77 are moved toward the right, the brake member 89 carried by the housing 78 moves out of engagement with the annular member 90, thereby freeing the capstan, the further movement of the rod 77 causing the plate 76 carried thereby to force the clutch disks 72 and 73 into engagement with each other so that they form a driving connection between the capstans 17-17 and the sleeve 18. Simultaneously the valve which controls the supply of lubricant to the die and drawing elements is opened by the arm 39 being turned counter-clockwise about its pivot 91 through the mechanism heretofore described. As the rod 159 is moved upwardly to operate the clutch mechanism, as above described,

the operator pulls outwardly on the knob 125 and when the block 151 has been moved upwardly, through the medium of casing 161 and rod 159, a distance sufficient to bring the lugs 149 opposite the wide portion of the slot 150, the rod 144 may be moved toward the left, as viewed in Figs. 6 and 7 until the said lugs rest beneath the projections 152 formed in the slot. When the rod 144 is in this position it supports the block 151 in its upwardly moved position, and the block in turn through the medium of the spring 156, which is stronger than the spring 87, holds the rod 159 in its upwardly moved position. The rod 159 through the lever system heretofore described, retains the housing 78 and shaft 77 in such position that the plate 76 locks the clutch disks 72 and 73 together. The rod 144 is retained in its locking position through the system of levers connecting it with the rod 126, the latter rod being locked in its outwardly moved position by means of the spring pressed pawl 130.

After the clutch mechanism has been actuated through the foot pedal (not shown) to connect the capstan with the driving mechanism and the said clutch has been locked through the actuation of the knob 125, the foot pedal may be released, which is returned to its initial elevated position by the weight of the casing 161 which moves downwardly a distance limited by the pin 162 and slot 163.

For a more detailed illustration and description of the mechanism for driving the take-up spool 61 at varying speeds to compensate for the varying diameters thereof as wire is stored on the spool, which mechanism includes a friction clutch the driving action of which is controlled by the tension of the drawn wire, reference is made to applicant's copending application, Serial No. 566,385, filed June 6, 1922. For a detailed disclosure and description of the mode of operation of the leverage mechanism 200 to vary the speed of the take-up spool 61 responsive to the tension on the drawn wire between the take-up spool and last reducing die, reference is made to my copending application, Serial No. 541,633, filed March 7, 1922, since this mechanism is identical with that disclosed in my application above referred to.

As is described in my said application, Serial No. 541,633, when the tension on the drawn wire is decreased below the proper tension, the leverage mechanism 200 is actuated to increase the speed of the take-up spool, and in this operation a link 201, which is one element of the said leverage mechanism, is moved downwardly. When the tension on the drawn wire is increased above the proper tension, the said link is moved upwardly. In the event that the wire breaks, the link 201 is caused to move downwardly a distance sufficient to move a plate 112 carried by the link into engagement with a collar 120 and cause a downward movement thereof. The collar 120 is carried by a rod 121 the upper end of which is pivoted at 122 (Fig. 6) to an arm 123 fast on a shaft 124 which also has secured thereto the spring pressed pawl 130. In the event that the wire breaks during the drawing operation and the rod 121 is depressed, which causes the arm 123 to turn the shaft 124 counter-clockwise, as viewed in Fig. 6. This movement of the shaft 124 disengages the pawl 130 so that the rod 126 is free to move inwardly to disengage the clutch mechanism within the capstan in the same manner that the said rod 126 is freed by disengaging the pawl 130 through an actuation of the knob 125, which operation has been previously described.

From the above it will be understood that the link 201 which is actuated responsive to the tension of the drawn wire to operate the mechanism for varying the speed of the take-up spool, also in the event that the strand breaks, actuates means for tripping the pawl 130 which releases the mechanism for disengaging the clutch mechanism mounted within the capstan to stop the operation thereof and as described before, simultaneously causes the valve 30 controlling the supply of lubricant to the die block 21 to be closed.

What is claimed is:

1. In a wire drawing machine, a die block, a die carried thereby, an element for drawing wire through the die, means for supplying lubricant to the die, and mechanism responsive to the tension of the wire for controlling the supply of lubricant to the die.
2. In a wire drawing machine, a die block, a die carried thereby, a drawing element, driving means therefor, means for supplying lubricant to the die carried by the die block, controlling means therefor, and mechanism operated automatically in the event that the wire breaks for operating the lubricant controlling means to discontinue the supply of lubricant to the die.
3. In a wire drawing machine, a die block, a die carried thereby, a drawing element, driving means therefor, means for supplying lubricant to the die, controlling means therefor, and mechanism for operatively disconnecting the drawing element from the driving means and for operating the lubricant controlling means to discontinue the supply of lubricant to the die in the event that the wire breaks.
4. In a wire drawing machine, a die block, a die carried thereby, a drawing element, driving means therefor, means for supplying lubricant to the die, controlling means therefor, and means interconnecting the drawing element and the lubricant con-

- trolling means for operatively disconnecting the drawing element from the driving means and to discontinue the supply of lubricant to the die in the event that the wire breaks.
5. In a wire drawing machine, a die block, a die carried thereby, a drawing element, driving means therefor, a clutch mechanism for operatively connecting and disconnecting the drawing element to and from the driving means, means for supplying lubricant to the die, controlling means therefor, and mechanism for operating the clutch mechanism to disconnect the drawing element from the driving means and for operating the lubricant controlling means to discontinue the supply of lubricant to the die in the event that the wire breaks.
6. In a wire drawing machine, a die block, a die carried thereby, a drawing element, driving means therefor, means for supplying lubricant to the die, controlling means therefor, a storage mechanism, and means controlled by the wire between the drawing element and the storage mechanism for operatively disconnecting the drawing element from the driving means and for operating the lubricant controlling means to discontinue the supply of lubricant to the die in the event that the wire breaks.
7. In a wire drawing machine, a die block, a die carried thereby, a drawing element, driving means therefor, means for supplying lubricant to the die in such quantity that it drains onto the drawing element, controlling means therefor, and mechanism for operatively disconnecting the drawing element from the driving means and for operating the lubricant controlling means to discontinue the supply of lubricant to the die in the event that the wire breaks.
8. In a wire drawing machine, a die block, a die carried by the die block, an element for drawing wire through the die, means for supplying lubricant to the die, a valve for controlling the lubricant supply, and mechanism for automatically closing the valve to discontinue the supply of lubricant to the die in the event that the wire breaks.
9. In a wire drawing machine, a die block, a die carried thereby, a drawing element, driving means therefor, means for supplying lubricant to the die, a valve for controlling the lubricant supply, and mechanism for operatively disconnecting the drawing element from the driving means and for closing the valve to discontinue the supply of lubricant to the die in the event that the wire breaks.
10. In a wire drawing machine, a die block, a die carried thereby, a drawing element, driving means therefor, means for supplying lubricant to the die, a valve for controlling the lubricant supply, and means interconnecting the valve and the drawing element for operatively disconnecting the drawing element from the driving means and for closing the valve to discontinue the supply of lubricant in the event that the wire breaks.
11. In a wire drawing machine, a die block, a die carried thereby, a drawing element, driving means therefor, a clutch mechanism for operatively connecting and disconnecting the drawing element to and from the driving means, means for supplying lubricant to the die, a valve for controlling the lubricant supply, and mechanism for operating the clutch mechanism to disconnect the drawing element from the driving means and for closing the valve to discontinue the supply of lubricant to the die in the event that the wire breaks.
12. In a wire drawing machine, a die block, a die carried thereby, a drawing element, driving means therefor, a clutch mechanism for operatively connecting and disconnecting the drawing element to and from the driving means, means for supplying lubricant to the die, a valve for controlling the lubricant supply, and means interconnecting the clutch mechanism and the valve for disconnecting the drawing element from the driving means and for closing the valve in the event that the wire breaks.
13. In a wire drawing machine, a die block, a die carried thereby, a drawing element, driving means therefor, means for supplying lubricant to the die in such quantity that it drains onto the drawing element, a valve for controlling the lubricant supply, and means interconnecting the drawing element and the valve for operatively disconnecting the drawing element from the driving means and for closing the valve to discontinue the supply of lubricant to the die in the event that the wire breaks.
- In witness whereof, I hereunto subscribe my name this 30th day of June A. D., 1924.
- JOHN NILSEN SELVIG.
